Letters Patent No 1963-Dated June 11th 1864

Design for a Watch Chain.

The schedule referred to in these Letters Patent and making part of the same.

To all Persons to whom these Presents shall come:

Be it known that I,

Augustus D. Varran (a resident of Attleboro in the County of Bristol and State of Massachusetts) have invented or produced a new and ornamental Design for a Watch Chain, and I do

hereby declare the same to be fully described in the following specification, and represented in the accompanying drawings, of which

Figure 1. is a side view, and

Figure 2. a top view of it.

The design in question is composed of a series of cannons, connecting links and eyes, arranged together substantially as shown in the said drawings in which a, a, a, &c. are the cannons; b, b, b, &c. the connecting links, and c, c, c, &c. the eyes. The cannons are arranged that the cascade of one shall be connected by a link with the muzzle of another, the link being an annulus or ring going through eyes applied to the muzzles and cascades.

2

OES. 1963

I claim the said design for a chain as comprised
of ordnance or canons and connections substantially as specified.
